UNITED STATES PATENT OFFICE.

FRANK L. FURBUSH, OF GRANITEVILLE, MASSACHUSETTS, ASSIGNOR TO C. G. SARGENT'S SONS CORPORATION, OF WESTFORD, MASSACHUSETTS, A CORPORATION OF MASSACHUSETTS.

SECTIONAL CONVEYER FOR DRYING MACHINES.

Application filed December 28, 1921. Serial No. 525,463.

To all whom it may concern:

Be it known that I, FRANK L. FURBUSH, a citizen of the United States, residing at Graniteville, in the county of Middlesex and State of Massachusetts, have invented certain new and useful Improvements in Sectional Conveyers for Drying Machines, of which the following is a specification, reference being had to the accompanying drawings.

This invention relates to conveyers, and particularly to sectional conveyers such as are used in drying machines for conveying wool, cotton, hair, etc., and the general object of my invention is the provision of a conveyer comprising a plurality of removable sections, so that should any part of any one or more sections become damaged, or incapable of performing its work, the damaged conveyer section may be easily removed and a new section inserted, thereby avoiding the expense of purchasing an entire new conveyer.

Still another purpose consists in the provision of improved means for use in connecting the sections of the conveyer to the chains, such that by simply forcing the chain laterally a section can be easily and very quickly removed, to permit the insertion of a new one.

A further object is to provide means whereby the sagging of the conveyer between the sprocket wheels thereof is prevented, and further to provide means for connecting the sections of the conveyer to the chains which will support the sections of the conveyer above the centers of the connecting means so that the outer faces of the sections may present practically a plain and unobstructed surface.

Other objects will appear in the course of the following description.

In the drawings:-

Figure 1 is a view showing the application of the improved sectional conveyer or apron to a drying machine;

Figure 2 is a cross sectional view on line 2-2 of Figure 1;

Figure 3 is a plan view of a portion of the conveyer or apron;

Figure 4 is a longitudinal sectional view on line 4-4 of Figure 3;

Figure 5 is a horizontal sectional view through a portion of the apron or conveyer

showing the tubes 12 and the pins 16, which engage the tubes;

Figure 6 is a sectional view of a modified form of connection between the apron or conveyer sections, showing the sections as extending from the upper portions of the tubular rods 12, so that the conveyer is flat or even on its top face;

Figure 7 is a longitudinal sectional view of a modified form of sectional conveyer or apron as applied to a drying machine;

Figure 8 is an enlarged plan view of a portion of the conveyer or apron, wherein the conveyer sections are of the same length as the links of the chains, which carry the conveyer sections;

Figure 9 is an enlarged detail perspective view of the links shown in Figure 8, showing how the conveyer sections are fastened to the links, which are the same length as the conveyer sections; and

Figure 10 is a sectional view of a modified form of connection between the apron or conveyer sections, wherein the holding pins are rectangular in cross section.

Referring to the drawings, 1 and 2 designate the opposed drums of a drying machine, over which the apron or conveyer travels. The shafts 3 of the drums carry sprocket wheels 4, with which the chains of the sectional conveyer engage. Interposed between the drums and adapted to support the upper and lower stretches of the chains are angle iron supports 6. The chains are made up of suitable links, such as flat strips 7, which are connected by the pins 8. The ends of the pins are headed as at 9, thereby retaining the links connected together in sequence. Suitable rollers 10 are mounted upon the pins 8, and engage with the angle iron supports.

The conveyer or apron proper is made up of a plurality of perforated or wire fabric sections 11, the ends of which are connected to tubular rods 12. In order to connect the sections to the rods, sheet metal strips are bent upon themselves to form sleeves 13, through which the rods 12 extend. The end portions 14 of the sheet metal strips clamp the upper and lower faces of the foraminous sections, and are riveted thereto as at 15. Obviously, as shown in Figure 5, the rods may be rectangular in cross section, and the sheet metal strips are bent to conform there-

to, with the end portions thereof riveted to the opposite faces of the perforated or wire fabric sections. The purpose of this modification will be hereinafter set forth.

5 The opposite chains at intervals are provided with transversely disposed pins 16, arranged in pairs. These pins pass through certain of the opposed links, and have their outer ends reduced as at 17. The reduced 10 ends of the pins are engaged through the outer links of the chains and are headed as shown at 18, to secure the pins in place. The inner ends of the pins are extended toward each other, and are adapted to detachably engage in the ends of the tubular rods, thereby 15 supporting the conveyer or apron sections upon the chains.

Obviously the apron or conveyer sections can be easily detached, by simply raising the 20 chains from engagement with the angle iron supports at a suitable point between the drums, and pulling the chain laterally, causing the pins to disengage from the tubular rods.

25 In Figure 7 the drums 1 and 2 shown in Figures 1 and 2 are omitted, and in lieu thereof octagonal sprockets 20 are employed. These sprockets are engaged by the chains 21, which are made up of alternate long and 30 short links 23 and 24. The long links 23 are substantially equal to the flat edges 22 of the sprockets. Mounted between the links 23 upon headed pins 25 are rollers 26, which engage the transverse semi-circular recesses 27 35 of the faces 22 of the sprockets, thereby preventing the chains from slipping relatively to the sprockets. As the chains travel from the angle iron supports 6 the rollers 26 are in a position to engage the semi-circular recesses 27 of the sprockets. The links 23 are arranged so that certain of said longitudinal edge portions will overlie the side faces of the sprockets, whereas the links 24 may engage upon short flat edges 28 formed 40 between the edges 22 of the sprockets. 45

In Figures 7, 8 and 9 the pins 29 (which correspond to the pins 16) have elongated reduced portions 30, which engage through the ends of the links 23 and the links 24, 50 thereby connecting the links, and at the same time holding the pins to the chains. The outer ends of the reduced portions 30 are headed at 31, so as to retain the links 23 and 24 in position and between the heads 55 31 and the shoulders 32.

The inwardly projecting portions 33 of the pins loosely engage the ends of the tubular rods 34, to which the conveyer or apron sections 11 are connected by means of the 60 sheet metal strips, which are bent upon themselves to form cylindrical sleeves 35. The flanges of the sheet metal plates are riveted or otherwise secured to the perforated conveyer or apron sections as at 36. Obviously 65 the conveyer or apron shown in Figures 7

and 8 function the same as the conveyer or apron shown in Figures 1 and 3, the only exception being that the construction is slightly modified, to the extent that the apron or conveyer sections are substantially 70 equal in length to the links 23, so that when the chains pass about the octagonal sprockets, the apron or conveyer sections will conform to the contour of the sprockets. When the chains shown in Figures 7 and 8 pass about 75 the sprockets, the rollers 26 may engage the semi-circular cavities or recesses 27, so that the chains will properly operate. It is obvious that though the drum is omitted in Figures 7 and 8, it may be included in this 80 construction, if so desired, it being obvious that the drum would then conform to the shape of the sprockets.

In Figure 10, I illustrate a modified construction in which the tubular rods 12' are 85 rectangular in cross section and the sheet metal sleeves 14' have those portions which engage the margin of the wire mesh 11' disposed tangentially to the axial center of the tubular rods 12' and practically flush 90 with the upper surface of said rods so that thus the wire mesh is supported above the centers of these rods and the conveyer apron has practically a plain surface from one drum to another. In Figure 6, I show a 95 like construction to that in Figure 10, but in this case the rods 12'a are cylindrical in form, the sleeves 13'a are also cylindrical in form to embrace said rods, and the margins of the sleeves, as at 14'a, extend tangentially 100 with respect to the axes of the rods 12'a.

The invention having been set forth, what is claimed is:—

1. In a conveyer, a frame, sprockets mounted in pairs therein, chains engaging said sprockets, drums, one mounted between the sprockets of each pair, angle supports on which the chains are supported and adapted to travel, apron sections between the sides of the opposite chains, inwardly projecting pins 105 carried by the chains and arranged in pairs, connectors carried by the adjacent ends of the apron sections and adapted to detachably receive said pins.

2. In a conveyer, a pair of opposed conveyer chains, revolute supports therefor, inwardly projecting pins fixed to the chains and arranged in pairs, conveyer sections between the opposed chains and having connectors at their adjacent ends for detachable 115 reception of said pins, whereby the sections may be removed by spreading the chains, without disconnecting the links of the chains.

3. In a conveyer, a pair of parallel conveyer chains, inwardly projecting pins fixed 125 to the links of the chains inward of the extremities of said links, said pins being arranged in pairs, and conveyer sections between the chains having connectors at their adjacent ends to detachably receive said pins, 130

- said connectors comprising tubular members, and sleeves, the sleeves engaging about the tubular members and having their end portions connected to the conveyer section, 5 said end portions being disposed to hold the conveyer sections flush with the upper surfaces of said connectors.
4. In a conveyer, a pair of opposed conveyer chains, revoluble supports therefor, 10 inwardly projecting pins carried by the chains and arranged in pairs, conveyer sections between the opposed chains and having connectors at their adjacent ends to receive said pins, said conveyer sections being 15 detachable from the pins by separating the chains laterally without disconnecting the links of the chains, angle supports for the chains, and rollers carried by the chains to engage said supports to hold the chains out 20 of contact with the supports.
5. In a conveyer, a pair of opposed conveyer chains, revoluble supports therefor, inwardly projecting pins carried by the chains and arranged in pairs, conveyer sections 25 between the opposed chains and having connectors at their adjacent ends to detachably receive said pins, angle supports for the chains, and rollers carried by the chains to engage said supports to hold the chains out 30 of contact with the supports, the construction and arrangement of said connectors with relation to the conveyer sections being such as to support the conveyer sections flush with the outer surface of said connectors. 35
6. In a conveyer, a frame, shafts mounted therein and provided with sprockets, chains conforming to and engaging said sprockets, tubular rods, pins pivotally connecting the 40 links of the chain and having inwardly extending lateral portions to telescopically engage the ends of the rods, thereby not only connecting the links, but also supporting the rods in position, conveyer sections be-
- tween the chains, and means for fastening 45 the conveyer sections to the rods.
7. A conveyer including parallel conveyer chains, each chain having inwardly projecting pins, and conveyer sections disposed between the chains, each section having at its 50 ends transversely extending tubular members, the opposite pins in the chains projecting into the opposite ends of each tubular member.
8. A conveyer including parallel chains, 55 each chain having inwardly projecting members, and conveyer sections disposed between the chains, each section having at its opposite ends transversely extending members telescopically engaging the corresponding 60 opposite pins of the chain, and clips embracing said transverse members and being attached to the adjacent end of the conveyer section.
9. A conveyer including parallel chains, 65 each chain having inwardly projecting members, conveyer sections disposed between the chains, each section having attached to its opposite ends transversely extending tubular sleeves, and members extending through 70 said sleeves and clamped thereby, said members having telescopic engagement with the inwardly projecting members on the chains.
10. A conveyer including parallel conveyer chains, each chain having inwardly projecting pins and conveyer sections disposed between the chains, each section having at its ends transversely extending tubular sleeves, each sleeve having portions 75 embracing the adjacent margin of the section and being riveted thereto, and tubular members passing through said sleeves and clamped thereby, the pins on the chains projecting loosely into said tubular members. 80
- In testimony whereof I hereunto affix my signature.

FRANK L. FURBUSH.
